ATTORNEY.

UNITED STATES PATENT OFFICE.

RUDOLF GAERTNER, OF NEW YORK, N. Y.

DESIGN FOR A PLATE OR SIMILAR ARTICLE.

48,933.

Specification for Design.

Patented Apr. 25, 1916.

Application filed March 10, 1916. Serial No. 83,436. Term of patent 3½ years.

To all whom it may concern:

Be it known that I, RUDOLF GAERTNER, a citizen of the United States, and resident of the borough of Manhattan, city, county, and State of New York, have invented a new, original, and ornamental Design for a Plate or Similar Article, of which the following is a specification, reference being

had to the accompanying drawing, forming part thereof, which drawing is a face view of a plate exhibiting my new design.

I claim:

The ornamental design for a plate or similar article, as shown.

RUDOLF GAERTNER.
